Charles Emmey, New York, N. Y.

Original application April 21, 1936, Serial No.
D-62,227. Divided and this application June
15, 1936, Serial No. D-63,292

Term of patent 7 years

To all whom it may concern:

Be it known that I, Charles Emmey, a citizen of the United States, residing in the city and county of New York, State of New York, have invented a new, original, and ornamental Design for Decorative Alphabet for Forming Appliquéd Monograms for Wearing Apparel or Similar Article, of which the following is a specification, reference being had to the accompanying drawing forming part thereof.

In the accompanying drawing, the figure is a plan view of the ornamental decorative alphabet for forming monograms for wearing apparel.

Each letter of the alphabet for forming monograms is a face view and is of no appreciable thickness.

The present application is a division of application bearing Serial No. D-62,227, filed April 21, 1936.

I claim:

The ornamental design for a decorative alphabet for forming appliquéd monograms for wearing apparel or similar article, substantially as shown and described.

CHARLES EMMEY.
